UNITED STATES PATENT OFFICE.

ASA C. ISHAM, OF MADISONVILLE, OHIO.

FEATHER DUSTER.

No. 894,833.

Specification of Letters Patent. Patented Aug. 4, 1908.

Application filed February 24, 1908. Serial No. 417,293.

To all whom it may concern:

Be it known that I, ASA C. ISHAM, a citizen of the United States of America, and resident of Madisonville, county of Hamilton, State 5 of Ohio, have invented certain new and useful Improvements in Feather Dusters, of which the following is a specification.

The object of my invention is a feather duster in which the handle is secured to the head by a simple means, which is firm, withstands wear in use, and permits the parts to 10 be coupled and uncoupled quickly. This object is attained by the means illustrated in the accompanying drawing, in which,

15 Figure 1 is a view in elevation of a duster embodying my invention. Fig. 2 is a detail sectional view, taken upon line $x-x$ Fig. 1, upon an enlarged scale. Fig. 3 is a view similar to Fig. 2 of a modified form.

20 Referring to the parts: A metal thimble, or ferrule, A, is secured to the head, B, of the duster, preferably by a bolt, C, which passes centrally through the head. Thimble, A, has at diametrically opposite sides and at its 25 upper edge, two L-shaped slots, a , each ter-

minating with a longitudinal notch, a' . The end of handle, E, is made of a size to fit snugly within thimble, A, and has pins, e' , e^2 , to engage the slots, a .

In the form shown in Fig. 2, a leaf spring, 30 G, is held in the bottom of thimble, A, by bolt, C, while in the form shown in Fig. 3, handle, E, has a similar spring, G' , secured to its end. In inserting the handle in its socket, pins, e' , e^2 , enter slots, a , the handle 35 is then given a rotatory motion carrying the pins into notches, a' , in which the spring, G, or, G' , retains them.

What I claim is:

In a feather duster the combination of a 40 head, a slotted thimble secured to the head, a handle with its end adapted to enter the thimble, a pin upon the handle to engage the slot and a spring within the thimble and adapted to hold the pin within the slot.

ASA C. ISHAM.
